UNITED STATES PATENT OFFICE.

HARVEY ZELL, OF DAYTON, OHIO, ASSIGNOR TO THE AMERICAN BOARD AND BOX CO., OF DAYTON, OHIO, A CORPORATION OF OHIO.

PAPER BOX.

No. 921,197.

Specification of Letters Patent.

Patented May 11, 1909.

Application filed November 30, 1908. Serial No. 465,052.

To all whom it may concern:

Be it known that I, HARVEY ZELL, citizen of the United States, residing at Dayton, in the county of Montgomery and State of Ohio, have invented certain new and useful Improvements in Paper Boxes; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 This invention relates to new and useful improvements in paper boxes or receptacles, which may otherwise be termed a combination of a wrapper and box. The box or receptacle is not made into such until it is 20 folded around the article which it is to contain.

It is especially designed for the reception 25 of butter which leaves the hands of the butter-maker in oblong rectangular prints of a conventional size. In dispensing butter in retail quantities, each print is laid upon the wrapper and the wrapper is folded around the same, and when completed forms a box or receptacle which is substantially of a 30 germ proof air-tight character and prevents any foreign substance entering the package.

While the wrapper or receptacle is especially designed for butter, it is equally available as a wrapper or container for other 35 articles of commerce which are sufficiently solidified to permit the wrapper to be folded around such articles and made into a completed box or receptacle, the article serving the purpose of a former as in the case of butter prints.

40 Preceding a detail description of the invention, reference is made to the accompanying drawings, of which—

Figure 1, is a plan view of the wrapper or 45 blank before it is folded around the article and completed as a box or receptacle as in Fig. 4. Fig. 2, is a perspective view showing the wrapper partly closed or folded around a butter print. Fig. 3, is a cross section of the 50 wrapper after it has been completely folded around a block or print of butter and sealed. Fig. 4, is a perspective view of the box or receptacle completed by being folded over and around the article.

55 In a detail description of the invention,

similar reference characters indicate corresponding parts.

The blank or wrapper which subsequently becomes a completed box or receptacle, is substantially square in outline and may be 60 varied more or less from such form without materially affecting the utility of the same. When so cut, the blank or wrapper is scored substantially as shown by the dotted lines in Fig. 1. A bottom 1, a front side 3, a rear side 2 and a top closure flap 6 are provided. The top closure flap 6 has a marginal extension or tongue 9 which bends upon a score line and is adapted to be inserted on the inner side of the front side 3 and between 65 said front side and the article 12 contained within the wrapper or box, said article being a print of butter. The top closure 6 is not joined to the two end wings or flaps 7 and 8 which form the inner top closure flaps and 70 lie below said top closure 6. These wings 7 and 8 are severed from the top closure 6 by slits 11 which permit said wings to be folded in over the top of the article and below said top closure 6. The flaps 7 and 8 75 thus forming the inner top closures are joined to the end extensions of the rear side 2 and bend upon score lines 14. Joining the bottom 1 are two flaps 4 and 5 which turn up 80 on score lines against the ends of the article 12 placed upon the bottom 1 and form the two main end closures of the box. Joining the front and rear sides 3 and 2 and the main 85 end closures 4 and 5 are rectangular folds 10 which are provided with diagonal score lines 15 upon which they are folded. These triangular folds 10 fold against the end closures 4 and 5 and thus reinforce or strengthen the 90 end closures.

In applying the wrapper and forming the 95 box, the article, for example, the print of butter 12, is placed upon the bottom 1; the ends 4 and 5 are then bent to stand upright 100 against the ends of the print of butter, or other article. The triangular folds 10 which join the front side 3 and the end closures 4 and 5 are formed by elevating said front side 3 against the adjacent side of the print of butter. The triangular folds are then folded 105 in against the end closures 4 and 5. The rear side 2 is then bent upright against the rear side of the print of butter thus serving as a form, and the triangular folds 10 which join the said rear side with the end closures 4 and 5 are folded in against said end closures 110

and against the folds which join the front 3 and said end closures 4 and 5, and which, as before stated, were first bent inwardly against said end closures 4 and 5. The folding of the 5 triangular folds which join the rear side 2 with the end closures 4 and 5, brings the wings or flaps 7 and 8 in a position to be folded inwardly on the score lines 14 and above the article serving as a form, to-wit—
10 the print of butter 12. The top fold 6 is then folded over upon the score line which separates it from the rear side 2 and it thus encloses the inner closures consisting of the wings 7 and 8. The locking tongue 9 is bent
15 along the score line separating it from the closure 6 and is inserted on the inside of the front side 3 and on the outside of the print of butter. and the wrapper thus becomes a completely folded box. The tongue 9 in
20 this position holds the closure 6 in position and also holds the end folds in position by engaging the outer edges of the wings 7 and 8. In using this combination of wrapper and box for butter, the same may be sealed by
25 means of a seal 16 which is adhered to the edge of the closure 6 and extends over and is adhered to the front side 3 as shown in Fig. 4.
From the foregoing description it will be apparent that the article within the box or
30 package is instrumental in maintaining the ends and the cover locked. For example, the extensions or wings 7 and 8 being held in position beneath the cover are instrumental in holding the ends of the box or package
35 closed, and the locking tongue 9 being held between the article within the package, and the inner side of the box or package serves to maintain the cover closed and the wings 7 and 8 against the article, so that there are no
separate means for locking the ends of the 40 box. See Figs. 2 and 4.
Having described my invention, I claim:
A paper box formed by folding a wrapper or blank about an article inclosed therein, said box when so folded having four sides 45 separated by longitudinal score lines, two of said sides providing the front and rear of the box, and two of said sides providing the bottom and top of the box, the bottom of said box having end extensions separated therefrom by transverse score lines and forming the inner end closures of the box, the front and rear sides having end extensions separated therefrom by transverse score lines, and separated from the end extensions of the bottom by parallel score lines, each of the end extensions of said front and rear sides having a diagonal score line upon which they are folded against said inner end closures, wings joining the end extensions of the rear side of 60 the box and folding inwardly beneath the top of the box, said wings being disconnected from the top of the box, and a locking tongue joining the top closure of the box and separated therefrom by a longitudinal score line, 65 said locking tongue being adapted to be inserted between the front side of the box and the article inclosed within said box, and to thereby maintain the box in its completed or folded shape while the article is contained 70 therein.

In testimony whereof I affix my signature, in presence of two witnesses.

HARVEY ZELL.
